CLAIM

The ornamental design for a shoe outsole, as shown and described.

DESCRIPTION

FIG. 1 is a front perspective view of a shoe outsole showing my new design;

FIG. 2 is a rear perspective view thereof;

FIG. 3 is a side view thereof;

FIG. 4 is a second side view thereof; and

FIG. 5 is a front view thereof; and,

FIG. 6 is a rear view thereof.

The broken lines showing the remainder of the shoe are for environmental purposes only and form no part of the claimed design.
